SPACER ELEMENT FOR TYPOGRAPHICAL MACHINES

Herman R. Freund, Brooklyn, N. Y., assignor to
Intertype Corporation, Brooklyn, N. Y., a corporation of New York.

Application June 6, 1947, Serial No. 753,129

11 Claims (Cl. 95—4.5)

1

This invention relates to improvements in spacer elements, commonly known as blanks or quads and employed in typographical line-composing machines for establishing separation between characters, and more especially between words, in composed lines of character-bearing elements from which may be reproduced lines of type matter useful for printing purposes.

More particularly, the invention is concerned with a quad or spacer element the thickness of which, in contrast to the variety of fixed thickness spacer elements heretofore used, may be adjusted so that the one element alone may be used to establish different amounts of separation at the points where it occurs in a composed line of elements.

An adjustable spacer such as herein provided is especially useful and advantageous in connection with typographical machines constructed and arranged to produce lines of type matter photographically, for example, a machine of the general organization disclosed in U. S. Patent No. 2,395,659, of which I am co-inventor, and the invention is herein disclosed by way of example as applied to a machine of this class.

Among the objects of the invention are the following: to provide an adjustable quad or spacer element capable of storage, assemblage, circulation and distribution in the manner of and by the well known organs used for like purposes in handling ordinary quads and character-bearing matrices in commercial line composing and type slug casting machines; to provide a spacer element having a minimum normal thickness but expandable to at least one other thickness, and having expanding means which is self-operative to maintain the element at such other thickness during circulation in the machine; to provide means for expanding such spacer element while contained in an assembled or composed line of elements, and means for restoring it to normal thickness prior to circulation through the distributing organs of the machine.

Other objects will be in part obvious and, in part pointed out hereinafter.

In the present embodiment, the spacer element as viewed flatwise has the marginal outlines, including the upper and lower projecting lugs and the distributing teeth, common to the well known blanks or quads and also to the character-bearing matrices long known and used in commercial typographical machines. Viewed edgewise, however, the element distinguishes from the solid one-piece construction of such known quads and matrices in that it comprises outer or side plates

made of resilient material and secured together flatwise toward their upper and lower ends in parallel relation but spaced apart as by means of upper and lower separating or body members. In the opening left between the assembled parts is inserted an adjustable slide adapted to move laterally edgewise to effect expansion and contraction of the element, said slide being provided with transverse apertures or holes, and the opposed flexible side plates being provided with correspondingly disposed depressions adapted to seat in such holes. The arrangement is such that when the slide is in its forward or inactive position the depressions mate with the holes and due to the springy nature of the side plates the latter assume a relaxed and parallel condition so that the element has its normal or minimum thickness, but when the slide is pressed in or rearwardly the holes become displaced relative to the depressions so that the flexible side plates are deflected or bowed outwardly and thereby expand the thickness of the element.

For actuating the adjustable slide to expand the element there is provided on the slide a forwardly extending tongue adapted to cooperate with a manually operated presser bar provided in the usual line-assembling elevator of the machine. For restoring the slide to normal position prior to distribution of the element, a member arranged to reciprocate to and from engagement with the rear edge of each element to hold it momentarily at the photographing position is used.

The foregoing and other objects, advantages and features of construction will be described hereinafter in detail in connection with the accompanying drawings which illustrate one embodiment of the invention. Obviously, the form and arrangement of the parts and their mode of operation, and the manner in which the invention is applied to one or another form of typographical machine may vary in many ways without departing from the spirit of the invention. It is therefore to be understood that the invention is limited only in so far as expressed in the claims.

In the drawings:

Figure 1 is a side elevation, on an enlarged scale, showing the spacer element of the invention with its adjustable slide in forward or normal position whereby the element assumes minimum thickness.

Figure 2 is a section taken on the line 2—2 of Figure 1.

Figure 3 is similar to Figure 1 but shows the

spacer element with its adjustable slide pressed rearwardly whereby the thickness of the element is expanded.

Figure 4 is an end elevation viewed from the right edge of the element shown in Figure 3.

Figure 5 is an exploded view, in perspective, showing the component parts of the element.

Figure 6 is a fragmentary view showing an expanded spacer element upon arrival at the photographing position, and showing the member provided for engaging and momentarily holding each element at such position and which operates, upon such engagement, to restore the adjustable slide of the spacer element to normal position.

Figure 7 is a fragmentary view, in section, of the lower end of a standard typographical magazine with spacer elements of the invention stored therein.

Figure 8 is a front elevation of the usual line-assembling elevator to which is applied the presser bar herein provided for actuating the adjustable slides of such spacers as may be contained in a line composed in the elevator.

Figure 9 is a section taken on the line 9—9 of the Figure 8 with the presser bar forward or inactive.

Figure 10 is a fragmentary section similar to Figure 9, but shows the presser bar in operated position for adjusting the slides of the spacer elements.

As already pointed out, the invention is herein disclosed by way of example as applied to a photo-composing machine of the general organization shown and described in U. S. Patent No. 2,395,659, and reference may be had to this patent for details of construction deemed unnecessary to dwell upon here. To explain briefly and to the extent necessary for a full understanding of the invention, apart from certain modifications required for photographic purposes the machine referred to embodies element storage, assembling and distributing devices long known and used in commercial typographical line composing and type slug casting machines. Further, the character-bearing elements employed, commonly called "matrices," have the familiar characteristics of those used in such known machines except that instead of the usual intaglio character in the narrow edge from which to cast, they carry a photographable character on a film plaque framed in the broad side of the body. An example of such photographable elements is shown and described in the patent hereinabove referred to and the edgewise thickness of the body of such elements varies in accordance with the setwise width of the characters respectively borne thereby, all as well known in connection with the standard slug casting matrices.

For photographic reproduction purposes the machine referred to is arranged to produce the lines of type matter letter-by-letter from composed lines containing such photographable character-bearing elements and containing word-space elements (blank matrices or quads) of fixed thickness. For producing successive lines all justified to a common desired length, the length of the composed line of elements is first measured to determine the total amount by which it is short of the justified length desired. The elements are then removed edgewise one-by-one from the leading end of the composed line and moved along a feed channel to a photographing position where the pointed end of a reciprocating finger engages a small V-shaped notch

in the front edge of the particular element to momentarily hold it at such position for exposure. Upon release by retreat of said finger the successively exposed elements are moved further along the feed channel to a discharging position from which they are distributed back to their respective places of storage on the machine. Upon each removal of an element from the composed line of elements a line advancing member acts to advance the remaining elements to the extent of the edgewise thickness of the particular removed element, and such advancing action is transmitted to the sensitized medium (film or paper) in order to present fresh areas thereof for receiving the successive photographic exposures. During each such advance the devices previously operating to measure the total amount of shortage of the line of elements as originally composed react, and such reaction operates to increment the extent of the particular advance by a portion of the measured amount of shortage, such portion being determined and governed by the thickness of the particular removed element. The total measured shortage is thus progressively distributed in increments among all of the reproduced characters and word spaces to form the justified line of type matter, and such manner of distributing line-shortage may aptly be termed "progressive justification."

As will be apparent to those familiar with the technic of typography and the practice of type composition, such distribution of line-shortage among letters as well as words materially improves typographical appearance since it avoids the frequently seen wide gaps resulting from the common practice heretofore of distributing all of the shortage equally among only the relatively few word spaces in a line. However, it will also be apparent that if the total amount of shortage is quite large its distribution by increments among letters and word spaces as well might result in the unpleasing effect of gaping letter spaces, especially in the case of short length lines.

The adjustable spacer shortly to be described affords convenient and effective means whereby, in a machine arranged to distribute line-shortage among letters as well as words, the operator or compositor may alter his initial word spacing and thus avoid the possibility of objectionably wide letter spacing when the line is finally reproduced. In other words, the adjustable spacer element herein provided affords the operator of the machine the opportunity, prior to the aforesaid "progressive justifying" action, to absorb, only between the words, some part of any excessive amount of line-shortage. Viewed in another light, the invention provides a single blank or quad spacer which is adjustable in thickness and thus capable of serving the purposes of several elements of different fixed thicknesses as heretofore necessary to employ in order to deal with difficult situations arising when excessive line shortage is encountered.

Referring to the drawings which show one convenient form of construction for the spacer element of the invention, the element comprises the thin opposed outer or side plates 1 and 2 which may be made of any resilient material such as spring steel, brass or even a suitable plastic material. The plates 1 and 2 are suitably secured together toward their upper and lower ends in parallel spaced relation, as by securement to the opposite parallel sides of upper and lower sep-

arators 3 and 4, respectively, in such manner that the marginal outlines of the plates coincide and the extreme top and bottom edges of the respective separators are flush with the corresponding edges of the side plates.

As evident, the foregoing parts so assembled provide an element having the marginal outlines of a standard matrix. Thus, the side plates carry the usual upper and lower lugs X, Y, and the separators 3, 4 carry similar lugs, these lugs serving in well known manner to support and guide the elements in the various organs of the machine. The upper separator 3 also carries the familiar distributing teeth 3a, and as plainly indicated the side plates are notched deep enough at the top to clear these teeth when the parts are secured together in the manner described.

In the opening extending edgewise through the spacer body and formed by the assembled separators and side plates is inserted the spacer adjusting slide 5 which is made to neatly fit between the side plates and is provided with a tongue 6 projecting from its front vertical edge, this tongue being used to press the slide rearwardly as later explained. The slide 5 is apertured, preferably by way of the two holes 7 and 8 drilled transversally through it, and the side plates are provided with depressions adapted, when the slide is disposed forwardly in the opening, as seen in Figs. 1 and 2, to register with and seat or engage in the respective holes from opposite sides thereof. Thus, as shown, the depressions 9, 10 in plate 1 seat in the holes 7 and 8 from the left side while the depressions 11, 12 in plate 2 seat in these holes from the right side. In this forward position of the slide 5 the element assumes its minimum thickness, the resilient side plates being relaxed and lying flat and parallel against the separators 3 and 4 as well as the slide itself, and the tongue 6 projects forwardly of the body of the element to about the same extent as do the upper and lower lugs X and Y, while the rear edge of the slide stands flush with the rear edge of the body.

Turning now to Figs. 3 and 4, it will be seen that the slide 5 has been pressed rearwardly so that its rear edge projects outwardly beyond the rear edge of the element to the extent that tongue 6 has receded into the edgewise opening in which the slide operates. Since in this position of the slide the holes 7 and 8 are displaced and no longer register with the depressions in the respective side plates the latter become bowed outwardly and thus increase the effective thickness of the element, the depressions in the side plates now bearing yieldingly against unapertured portions of the opposite sides of the slide, all as clearly indicated in Figs. 3 and 4. It will be evident that due to the springy nature of the side plates 1 and 2 the depressions therein will exert sufficient pressure against the slide 5 to firmly hold the latter in its rearward or expanding position until it is forcibly acted upon to press it to the forward position where the depressions may snap into the holes and so restore the element to its minimum thickness.

The space indicated at 13 in Fig. 2 represents clearance for allowing the element to contract slightly in vertical height, as it must do when the side plates are distorted or bowed outwardly by the slide and the depressions.

Adjustable spacer elements such as just described are capable of storage in the well known channeled magazines employed in commercial

typographical machines for storing fonts of character-bearing matrices and the ordinary fixed thickness blank or quad matrices. Thus, in Fig. 7 two of the adjustable thickness spacers of the present invention are shown, held by the usual rocker escapement 14, in one of the channels of the magazine M. It will be observed that when so stored the spacers are in normal or relaxed condition with their front edges, from which the tongues 6 project, facing upward. From this it will be evident that the tongues 6 in no way conflict with the functioning, in well known manner, of the rocker escapement. It will also be evident that since the tongues 6 project no further from the front edge of the body of the elements than do the usual upper and lower lugs X and Y, such tongues will in no way interfere with passage of the elements through the usual assembling organs of the machine. And while the usual distributing organs of the machine are not herein shown, those familiar with typographical machines will immediately recognize that the tongue 6, disposed as it is at the front edge of the element, presents no obstacle to the free passage of the element through these organs.

Referring to Figs. 8, 9 and 10, character and spacer elements when released from the storage magazine are directed by the familiar downwardly inclined belt (not shown) over the rotating star wheel 15 which flips the successively arriving elements to a vertical position onto supporting rails 16, 17 extending longitudinally along front and rear walls of the usual assembling elevator E. The elements accumulate edgewise in line formation on these rails and as the successive elements arrive the line resistant finger 18, secured as usual to the assembler slide bar 19, is advanced, in well known manner from a line starting position adjacent to the star wheel 15. The finger 18 is free to advance, as usual against the restraining action of a light spring (not shown), until an adjustable stop (not shown) which the operator sets to the line-measure desired is encountered by a stop block (not shown) on the slide bar 19. However, advance to this exactly "full-line" extent will rarely occur since in practice at least some shortage is always left for line justification purposes. In addition to an em scale by which the aforesaid stop is set the assembling elevator is provided with the usual em scale 20 by which the growth of the line may be observed by sighting the position of the finger 18 relative to this scale. When composition of the line is completed the elevator E is raised manually, as well known, to deliver the line to the reproducing mechanism of the machine.

As well known, the elevator E is provided with a so-called "high alignment" rail 21 which extends longitudinally of the assembling channel and is arranged to reciprocate for and aft. Since the "high-alignment" function of rail 21 is not used in the photocomposing machine hereinabove referred to and to which the present invention is applied, this rail is conveniently modified so as to serve as an actuator for the slides 5 of the spacer elements of the invention. To this end the rail 21 is provided along its inner edge with an upstanding lip 22 of such height as to lie opposite the tongues 6 of the spacers when the latter rest on the element supporting rails 16, 17. Rail 21 thus serves as a presser bar by which to press rearwardly the slides 5 of such spacers as may be present in a composed line of elements, thus to increase the thickness of

such spacers and thereby absorb at least some part of any excessive amount of line-shortage that might be judged to exist.

For operating the rail or presser bar 21 to actuate the slides 5, the bar is operatively connected, as usual, with the upright rocker arms 23, 24 pinned to the cross shaft 25, the latter being supported in bearing lugs 26, 27 integral with or otherwise secured to the front wall of the elevator E. Pinned to shaft 25 is a finger lever 28 by which this shaft may be rocked whereby to operate the presser bar. A spring 29 serves to urge the rail or bar 21 forwardly to its normal position as seen in Fig. 9.

Decision as to whether or not to use the presser bar 21 is up to the operator but is not necessarily a matter of special skill or expert judgment. Thus, operators in general are familiar with the fact that for good typography lines should be set as full as possible and that gaps between words should be kept to a minimum. They are also familiar with the fact that if the line measure being set is quite short it is more difficult to completely fill out a line by adding a word or by breaking a word properly into syllables in order to fill out the line. Of course with the facility of "progressive justification" or incremental distribution of line shortage between letters as well as words—as in the photo-composing machine already referred to—operators will realize that a somewhat greater amount of line shortage may be disposed of or absorbed without resulting in any perceptible or at least objectionable increase in letter spacing. However, without the adjustable spacer of the present invention adjustments to take-up excessive shortage would entail either removing word-space elements of a fixed minimum thickness and replacing them by elements of a greater fixed thickness, or else resetting the line entirely. Such practice is not only tedious and time-consuming but indeed inadequate for economical and efficient production.

As a general guide in determining whether or not to use the bar 21, the rule may be followed that the composed line should be filled to the extent that it is not more than 1-em short of the line measure being set. For example, assuming that the measure being set is 18-ems, the length of the line of elements between finger 18 and star wheel 15 in Fig. 8 is indicated by the position of finger 18 relative to scale 20 as being more than 1-em short of the desired 18-ems. Accordingly the presser bar 21 should be used to expand the spacers present between the words in this composed line of elements, thereby to take-up or absorb some of the excessive shortage before delivering the line, in well known manner, to the reproducing mechanism for distribution, by the "progressive justifying" action already referred to, of the still remaining amount of shortage among the letters as well as the words.

The operated position of the presser bar 21, 22 after pressing the slides 5 rearwardly is shown in Fig. 10, it being understood that immediately upon actuating the slides the presser bar retracts to the forward position in Fig. 9 under the influence of spring 29. It will also be understood that as the spacers are expanded the finger 18 advances along the scale 20 to the extent that the length of the line is increased between the star wheel and the finger, thus enabling the operator to observe from the scale the amount of

shortage remaining after operating the presser bar.

It should be pointed out here that the amount by which the length of a composed line may be increased, through adjustment of the expandable spacers in the foregoing manner, will depend upon the number of such spacers in the composed line and upon the expansibility of the spacer elements themselves. The spacer element herein provided may be constructed to provide one or another minimum thickness, for example, thirty, thirty-five or forty thousandths of an inch. But the expansibility will depend of course upon the depth of the depressions in the side plates. Thus, to attain twenty thousandths expansion the depressions would be made ten thousandths deep and in such case the separators and slide would have to be of such thickness, at least twenty thousandths in order that such depth depressions would be free to seat fully from opposite sides of the holes. The depth of the depressions and the thickness chosen for the separators is a purely arbitrary matter and may be varied to meet different conditions and requirements.

Assuming that the spacer elements of the invention have been expanded, by operation of the bar 21, means is provided for restoring the slides 5 to their normal or forward position prior to passage of such elements through the distributing organs of the machine. Such restoring means is shown in Fig. 6 and comprises the pointed reciprocable finger 30 which, in the photo-composing machine herein referred to, operates to engage each element upon its arrival, along the feed channel 31, at the photographing position and to hold it momentarily aligned optically and at rest at such position for exposure. For cooperating with the pointed end of finger 30 to align each element at the photographing position, the spacer elements herein disclosed are provided on their rear edge with the same V-shaped notch N as is provided in the corresponding edge of each character-bearing element.

As clearly shown in several of the drawings, the notch N is formed in the side plates 1, 2 of each spacer element and in the adjustable slide 5. Accordingly, when a spacer arrives at the photographing position with its slide 5 projecting rearwardly, finger 30 in its forward stroke first engages the notch in the slide 5, and since this slide is free to move forwardly the finger 30 so moves it until stopped upon encountering and fully engaging the correspondingly notched portion in the two side plates of the spacer. At this time the slide is fully restored to its normal or forward position with the tongue 6 projecting from the front edge of the element, the depressions in the resilient side plates having snapped into the holes in the slide whereby the plates become relaxed and thus restore the element to its minimum thickness.

From the foregoing it will be clear that the invention provides a blank or quad spacer element which is adjustable in thickness and provides means for adjusting such element to expand it and for restoring it to normal or minimum thickness; that such element affords convenient and efficient means for taking up excessive line-shortage by enlarging the word spaces in a composed line of elements before such line is utilized for reproduction purposes.

I claim:

1. A typographical spacer having the marginal

outlines of a standard matrix, said spacer comprising opposed side plates formed from resilient material and secured together flatwise toward their upper and lower ends in parallel spaced relation, a member slidable edgewise to different fixed positions in the space between said side plates, and cooperating means so formed and relatively disposed on said member and said plates that in one position of said member the side plates stand relaxed and in parallel relation whereas in another position of said member the side plates are flexed and held in oppositely outwardly bowed relation.

2. A typographical spacer having the marginal outlines of a standard matrix, said spacer comprising opposed side plates formed from resilient material and secured together flatwise toward their upper and lower ends in parallel spaced relation, a member slidable fore and aft in the space between said side plates and provided with at least one transverse aperture, a depression formed in the respective side plates and engageable in said aperture from opposite sides thereof to maintain the parallel relation of the side plates, and a tongue projecting from one edge of said member for sliding it to a position wherein its aperture is displaced relatively to said depression and the side plates are held outwardly bowed to the extent of the depth of the depressions.

3. A typographical spacer having the marginal outlines of a standard matrix, said spacer comprising opposed side plates formed from resilient material and secured in parallel relation flatwise to upper and lower separators providing between them and the side plates an opening edgewise through the spacer, a slide formed to neatly fit said opening and adapted for limited movement edgewise therein between forward and rearward positions, said slide having transverse apertures and the side plates each having depressions formed therein at points such as to engage in said apertures to maintain the side plates parallel when the slide is in forward position, and a tongue on the slide projecting forwardly of the opening for moving the slide rearward to disengage said apertures and depressions and thereby increase the thickness of the spacer to the extent that the side plates are flexed outwardly by bearing of the depressions against unapertured portions of the slide.

4. A typographical spacer having the marginal outlines of a standard matrix, said spacer comprising opposed side plates formed from resilient material and secured in parallel relation flatwise to upper and lower separators whereby to provide between the plates an opening edgewise through the spacer, depressions formed in said side plates and protruding into said opening from opposite sides thereof, and a slide having apertures formed therein and adjustable in said opening from a position wherein said apertures accommodate the depressions and the side plates are relaxed and parallel to a position wherein the apertures are displaced relatively to the depressions and the latter in consequence hold the side plates in an outwardly bowed relation.

5. A typographical spacer having the marginal outlines of a standard matrix, said spacer comprising opposed side plates formed from resilient material and secured in parallel relation flatwise to upper and lower separators, said separators and plates presenting between them an opening edgewise through the spacer, a slide adjustable fore and aft to different fixed positions in said

opening and cooperating means formed on said slide and the respective side plates for yieldingly holding the slide in one or another position of adjustment and for holding the side plates in outwardly bowed relation in one of such positions.

6. A spacer element adapted for use in a typographical machine and for expansion and contraction in edgewise thickness, said element comprising opposed side plates made of a resilient material and secured in parallel relation flatwise to upper and lower separators whereby to provide an opening through the element extending from the front to the rear edge thereof, and a separator member longer than said opening and shiftable edgewise therein between positions wherein either its front or its rear edge is flush with the corresponding edge of the element, said member and the side plates having cooperating portions formed and relatively disposed in such manner that in response thereto as said member is shifted from one to the other of said positions the side plates flex between outwardly bowed and relatively parallel dispositions, and actuating means in the machine for shifting said member from one to the other of said flush positions.

7. A spacer element adapted for use in a typographical machine and for expansion in edgewise thickness, said element having similarly outlined resilient side plates secured together flatwise toward their upper and lower ends in parallel spaced relation and provided with portions protruding into the opening edgewise between the plates, and a member shiftable fore and aft in said opening between positions flush either with the rear or the front edges of the side plates, said member having portions which in the respective flush positions clear and encounter the protruding portions of the side plates, the edgewise thickness of the element being governed by flexing of the side plates between a parallel and an outwardly bowed relation and vice versa according to the flush position to which said member is shifted.

8. A typographical spacer having the marginal outlines of a standard matrix and expandable in edgewise thickness, said spacer comprising opposed resilient side plates secured in parallel relation flatwise to upper and lower separators providing between them and the plates an opening edgewise through the spacer, a member having thick and thin portions and shiftable fore and aft in said opening between positions wherein a limited portion projects beyond either the front or the rear edge of the side plates and separate means in the machine cooperative with the respective edges of the side plates for shifting said member to the extent of its projecting portion, and means on the inner opposed faces of the side plates which engage the thick or the thin portion of said member according to the shifted position of the latter and operate when said member is shifted to cause the side plates to flex between a parallel and an outwardly bowed relation.

9. In a typographical photo-composing machine equipped with an assembling elevator for supporting a composed line of character and word-space elements from which to produce, letter-by-letter, a line of type matter and with photographing means including a reciprocable finger for holding each element at a photographing position, the combination of word-space elements having resilient side plates secured together flatwise in parallel spaced relation and

11

having a slide shiftable edgewise between flush-rear and flush-front positions in the space between the plates, said slide and said plates having cooperating means formed thereon and cooperating to cause the plates to flex between a parallel and an outwardly bowed relation according to the flush position of said slide, and a presser bar in the assembling elevator for shifting the slide to flush-front position wherein the side plates are outwardly bowed, the reciprocable finger at the photographic position operating to shift and restore the slide to flush-rear position wherein the side plates flex to a parallel relation.

10. In a typographical photo-composing machine having an assembling elevator for supporting a composed line of character and word-space elements from which to produce a line of type matter and having a photographing position and means for leading the elements singly and successively to such position for exposure to produce said line of type matter, the combination of word-space elements having resilient flatwise opposed side plates and a slide shiftable edgewise between the plates and between positions flush with the rear or the front edges thereof, the slide and the plates having portions formed and disposed to cooperate and maintain the plates in parallel or in outwardly bowed relation in said positions, respectively, of the slide, means in the assembling elevator for shifting to the flush-front position the slides of the word-space elements present in the composed line of ele-

12

ments to increase the length of said line to the extent that the side plates are bowed outwardly, and means at the photographing position for shifting the slide of each element to the flush-rear position to restore the side plates to a parallel relation.

11. In a typographical photo-composing machine having an assembling elevator for supporting a composed line of character and word-space elements from which to produce a line of type matter and having a photographing position and means for leading the elements singly and successively to such position for exposure to produce said line of type matter, the combination of word-space elements having resilient flatwise opposed side plates and a slide having thick and thin portions and shiftable edgewise between the plates to positions flush with either the rear or the front edges thereof, a portion of said slide extending beyond one edge of the plates in either position of the slide, a longitudinal rail in the assembling elevator for shifting the slides of the spacers in a composed line of elements to the flush-front position wherein the thick portions of the slides flex and hold the side plates in an outwardly bowed relation, and a reciprocating member at the photographing position for shifting the slide of each element to the flush-rear position wherein the side plates flex inwardly against the thin portions of the slides.

HERMAN R. FREUND.
